UNITED STATES PATENT OFFICE

WALTER J. STUBER, OF PHILADELPHIA, PENNSYLVANIA, ASSIGNOR TO CAREY-MCFALL CO., OF PHILADELPHIA, PENNSYLVANIA, A CORPORATION OF PENNSYLVANIA

CURTAIN

Application filed March 20, 1930. Serial No. 437,484.

This invention relates to window curtains, and particularly to those used in automobiles of the closed types. The invention particularly relates to the draw stick or rod usually provided at the free end of the curtain, for the purpose of facilitating the raising and lowering of the curtain.

Prior to my invention it has been customary to use wooden draw sticks in the curtains and to place the draw stick in a hem formed at the free end of the curtain, the curtain fabric usually being sewed together at the ends of the stick thereby closing the ends of the hem in which the stick is located so that the ends 15 of the stick would not show.

In automobiles of the closed types it is customary to provide guide wires or cords at each side of the curtain, to prevent flapping of the curtain when the car is in motion. 20 These guide cords extend along the side edges of the curtain usually being secured to the window frame at a point adjacent the curtain roller and at, or adjacent, the bottom of the window. It has been the usual practice 25 to place a screw eye in each end of the stick and to run the guide cords through these screw eyes, so that the curtain may be readily raised and lowered.

The wooden draw sticks have many disadvantages, for example, if the stick be of a small size, as to make for better appearance, such stick is frequently broken by a person in raising and lowering the curtain. Sticks made of a larger size, for the purpose of giving strength thereto, are bulky and unsightly.

In order to provide a strong relatively small draw stick manufacturers have considered the use of a metal rod in place of the wooden draw stick. Metal draw rods also 40 present many problems to the manufacturers, namely the problem of securing an eye to the curtain adjacent its free end for the accommodation of the guide cords; also the ends of the rod have a tendency to wear 45 through the curtain fabric, due to the vibration of a car in motion; another objection being that the curtain fabric, being susceptible to shrinkage, exposes the ends of the metal rod.

50 The object of the present invention is to

provide a metal draw rod which will be light in weight and small of size and still be sufficiently rigid to function properly.

Another object of the invention is to secure the rod in the hem of the curtain in such a manner that the ends of the rod will at no time be exposed by shrinkage of the curtain, the rod itself functioning as a means to prevent such shrinkage, and the means by which the rod is secured in the curtain hem also functioning as the eyes for the guide cords, all as will be more fully disclosed hereinafter, reference being had to the accompanying drawing, of which:

Fig. 1 is a front view of a curtain embodying my invention;

Fig. 2 is a side elevation of the structure shown in Fig. 1;

Fig. 3 is a fragmentary plan view of one end of the structure shown in Figs. 1 and 2;

Fig. 4 is a sectional view taken on the line 4—4, Fig. 1;

Fig. 5 is a sectional view taken on the line 5—5, Fig. 1, and

Fig. 6 is a sectional view taken on the line 6—6, Fig. 5.

In the drawings, an ordinary curtain, such as are used in automobiles of the closed type, is illustrated at 1, the curtain being wound on an ordinary roller 2 supported in brackets 3 and 4, in the usual manner. The free end of the curtain is provided with the usual form of hem 5. Within the hem 5 I place a round metal rod 6 of relatively small diameter and of a length slightly less than the width of the curtain.

Each of the respective ends of the rod 6 is flattened, as illustrated at 7, and these flattened portions are bored, as indicated at 8, for the reception of a tubular rivet 9, which passes through the opening 8 in the rod and through the sides 10 and 11 of the hem 5, the said tubular rivet being flanged as illustrated at 12 and 13 and these flanges being pressed tightly down against the sides 10 and 11 of the hem 5, to securely hold the rod in place within the hem of the curtain and to prevent fraying of the curtain material around the rivets.

The usual guide cords or wires 14, 14 pass

through openings 15 formed in the curtain brackets 3 and 4 and downwardly along the side edges of the curtain and through the openings 16, 16 of the tubular rivets 9, 9, the guide cords being secured at their lower ends by any suitable means, such as nails 17 having plain or ornamental heads as desired.

From the above description, it will be obvious that I am able to successfully employ a small metal draw rod for an automobile curtain, and that by securing the rod within the hem, in the manner described, relative movement between the rod and the curtain fabric is prevented, thereby obviating wear in the fabric. The curtain fabric is also prevented from shrinking and exposing the ends of the metal rod; and the tubular rivets function not only as a means for securing the rod in the curtain hem but also as the guide eyes for the guide cords of the curtain.

I claim:

1. The combination with a window curtain having a hem formed therein, of a draw rod located in said hem and provided with an opening at each of its ends adjacent the respective side edges of the curtain, and means passing through that portion of the curtain material forming the said hem and through the opening in the rod, at each side of the curtain, to hold the curtain taut intermediate its opposite ends and for securing the said rod in said hem.

2. The combination with a window curtain having a hem formed therein, of a draw rod located in said hem and provided with an opening at each of its ends adjacent the respective side edges of the curtain, and a rivet passing through that portion of the curtain material forming the said hem and through the opening in the rod, at each side of the curtain, to hold the curtain taut intermediate its opposite ends and for securing the rod in the hem of the curtain.

3. The combination with a window curtain having a hem formed therein, of a draw rod located in said hem and provided with an opening at each of its ends adjacent the respective side edges of the curtain, and a tubular rivet passing through that portion of the curtain material forming the said hem and through the opening in the rod, at each side of the curtain, for securing the rod in the hem of the curtain and providing eyes at the respective side edges of the curtain for guide cords to pass through.

4. The combination with a window curtain having a hem formed therein, of a draw rod located in said hem and provided with an opening at each of its ends adjacent the respective side edges of the curtain, and a tubular rivet passing through that portion of the curtain material forming the said hem and through the opening in the rod, at each side of the curtain, for securing the rod in the hem of the curtain and providing eyes at

the respective side edges of the curtain for guide cords to pass through, said tubular rivets having end flanges pressed tightly against the curtain material around the rivet openings to prevent fraying of the curtain material around said openings.

5. The combination with a window curtain having a hem formed therein, of a metallic draw rod located in said hem and provided with an opening at each of its ends adjacent the respective side edges of the curtain, and means passing through that portion of the curtain material forming the said hem and through the opening in the rod, at each side of the curtain, to hold the curtain taut intermediate its opposite ends and for securing the said rod in said hem.

6. The combination with a window curtain having a hem formed therein, of a round metallic draw rod of relatively small diameter located in said hem and provided with an opening at each of its ends adjacent the respective side edges of the curtain, and means passing through that portion of the curtain material forming the said hem and through the opening in the rod, at each side of the curtain, to hold the curtain taut intermediate its opposite ends and for securing the said rod in said hem.

7. The combination with a window curtain having a hem formed therein, of a round metallic draw rod of relatively small diameter flattened adjacent its opposite ends and located within said hem, said flattened portions being provided with openings disposed adjacent the respective side edges of the curtain, and tubular rivets passing through said openings and through the curtain material adjacent thereto, providing means for securing the rod in the curtain and also providing eyes for curtain guide cords to pass through.

8. The combination with a window curtain having a hem formed therein, of a round metallic draw rod of relatively small diameter flattened adjacent its opposite ends and located within said hem, said flattened portions being provided with openings disposed adjacent the respective side edges of the curtain, tubular rivets passing through said openings and through the curtain material adjacent thereto, providing means for securing the rod in the curtain and also providing eyes for curtain guide cords to pass through, and flanges on the tubular rivets overlying and pressed tightly against the curtain material surrounding the rivets, to prevent fraying of the curtain material around the rivets.
